CRYSTAL GRINDER ATTACHMENT FOR
SUCTION CLEANERS

Eugene F. Martinet, Cleveland, Ohio, assignor to
The P. A. Geier Company, Cleveland, Ohio, a
corporation of Ohio

Application May 16, 1949, Serial No. 93,434

6 Claims. (Cl. 43—124)

1

The invention relates to suction cleaners, and more particularly to a crystal grinder attachment for a suction cleaner for blowing pulverized crystals of a chemical reagent for demothing, purifying or fumigating, onto floor coverings, clothes and the like, or into storage closets, compartments, drawers, containers and the like for such articles.

Attachments for suction cleaners have been provided for discharging crystal vapors with the air blown through a blower tool attached to a cleaner. However, such vapors are not effective or sufficient where it is desired to kill or destroy moths, insects and the like, or to treat articles to prevent the existence of moths and insects therein.

Other attachments for suction cleaners have been provided in which crystals are discharged into a compartment having a screened outlet and the crystals, carried by air currents passing through the compartment, are abraded against the screen until crystal particles sufficiently fine are produced to pass through the screen and to be discharged with the air passing therethrough. Such constructions, however, are ineffective and inefficient in operation and must be operated for a long time for discharging the desired or required amount of crystals for killing moths and the like in the area or compartment treated.

My prior Patent No. 2,179,665 shows a crystal grinding mechanism which is most efficient in quickly breaking up moth destroying crystals to the desired degree of fineness. However, the crystal grinding mechanism in said prior patent is directly connected to and driven by the suction cleaner motor which presents a number of difficulties.

First, the supply of crystals to be ground is located in a compartment communicating with the grinder mechanism on the suction cleaner itself and remote from the discharge nozzle, and therefore control of the crystal feed to the grinder must be exercised at the cleaner location. However, convenience in operation requires that control of starting and stopping the flow of crystals should be available at the location of the nozzle from which crystal-laden air is blown when a crystal distributing operation is being performed in a closet, on the floor, in and underneath furniture, and into clothes and the like.

Second, the direct connection of the crystal grinding mechanism with the suction cleaner motor creates complications. The housing of the crystal supply and the mounting and driv-

2

ing of the grinding mechanism on the suction cleaner proper and in connection with the suction cleaner motor, from a mechanical standpoint, creates difficulties in the design and construction of the cleaner air passages and of the mounting and supporting mechanism for the motor and grinding device. Furthermore, the permanent mounting and housing of the grinding mechanism in the normal exhaust or blower passage of the cleaner reduces the amount of suction available at the normal suction nozzle of the cleaner when the equipment is not used for blowing crystals but is used in the normal manner as a cleaner.

Third, when a cleaner with the crystal grinding construction of the type illustrated in my prior patent is stopped with the feed valve from the crystal supply to the crystal grinder open, improperly, the grinder case will load with crystals and under certain atmospheric conditions, the crystals will cake in the grinder chamber and around the grinder fan. Such condition may not be noticed by the operator but can seriously damage the cleaner mechanism and motor when the cleaner is started at a later time.

Fourth, in my prior patented structure, the speed of the main cleaner motor determines and limits the speed of the grinder fan, and it is ordinarily desired to operate the cleaner motor and the grinder fan at different speeds for the most satisfactory operation of each.

Accordingly, it is an object of the present invention to provide an improved unitary crystal grinder attachment for a suction cleaner which is adapted for being held in a hand of the user and which may be located immediately adjacent a blower discharge nozzle at the end of a flexible hose attached to a cleaner.

A further object of the present invention is to provide such an improved crystal grinder attachment for a suction cleaner which will rapidly grind crystals to be discharged from a blower nozzle flexibly connected with the outlet end of a suction cleaner, right at the blower nozzle and without reference to the location of the cleaner, so that feeding of crystals to the grinder may be controlled in connection with manipulating the nozzle and directing the crystal-laden blast discharged from the nozzle.

Furthermore, it is an object of the present invention to provide an improved crystal grinder attachment for a suction cleaner which avoids mechanical complications in mounting and sup-

porting the cleaner motor and in constructing the blower air passages in the cleaner per se.

Also, it is an object of the present invention to provide an improved crystal grinder attachment for a suction cleaner which is removed from connection with the cleaner during normal operation of the cleaner so that it does not interfere with the amount of suction available at the cleaner suction nozzle when the cleaner is used in a normal manner.

Also, it is an object of the present invention to provide an improved crystal grinder attachment for a suction cleaner which cannot damage the cleaner mechanism per se in the event crystal particles become caked in the grinding mechanism.

Moreover, it is an object of the present invention to provide an improved crystal grinder attachment for a suction cleaner in which the crystal grinding mechanism may be rotated at a different or higher speed than the cleaner fan to enable greater flexibility in the time and character of grinding than if the grinding mechanism were directly connected to the suction cleaner motor.

Finally, it is an object of the present invention to provide an improved crystal grinder attachment for a suction cleaner having a simplified arrangement of parts, permitting economical manufacture, and convenience in use.

These and other objects and advantages apparent to those skilled in the art from the following description and claims may be obtained, the stated results achieved, and the described difficulties overcome, by the devices, constructions, arrangements, combinations, sub-combinations, parts, elements, discoveries and principles which comprise the present invention, the nature of which is set forth in the following general statement, a preferred embodiment of which—illustrative of the best mode in which applicant has contemplated applying the principle—is set forth in the following description and shown in the drawings, and which are particularly and distinctly pointed out and set forth in the appended claims forming part hereof.

The nature of the invention may be stated in general terms as preferably including in a unitary attachment for suction cleaners for grinding crystals and which is adapted for being held in a hand of the user, a housing including a crystal storage compartment, a grinding compartment, and a driving compartment; a valve controlled opening communicating between the storage and grinding compartments; a passage communicating between the driving and grinding compartments; an air blast inlet for the driving compartment; an air blast outlet for the grinding compartment; air turbine fan means in the driving compartment; crystal grinding blade means in the grinding compartment; and means connecting the air turbine and grinder blade means for driving the grinder blade means by the air turbine, whereby when the attachment inlet is connected with an air blast blown from the blower outlet of a suction cleaner the air blast passes through the driving and grinding compartments and is discharged through the air blast outlet and rotates the air turbine means thereby rotating the grinder means to grind crystals introduced into the grinding chamber by manipulation of the valve so that ground crystal particles are entrained in the air blast and discharged from the attachment outlet therewith.

By way of example, a preferred embodiment

of the improved crystal grinder attachment for suction cleaners is illustrated in the accompanying drawings forming part hereof wherein:

Figure 1 is a general perspective view of a suction cleaner having a hose attached to the blower outlet thereof provided with an embodiment of improved crystal grinder attachment at the end of the hose and associated with the blower discharge nozzle and shown in operation for blowing pulverized material onto an upholstered chair;

Fig. 2 is an enlarged transverse sectional view of the improved crystal grinder attachment taken on the line 2—2, Fig. 3;

Fig. 3 is a plan sectional view of the improved crystal grinder taken on the line 3—3, Fig. 2 with certain parts broken away;

Fig. 4 is a plan sectional view similar to Fig. 3 but taken on the line 4—4, Fig. 2;

Fig. 5 is a fragmentary sectional view of the attachment outlet taken on the line 5—5, Fig. 2;

Fig. 6 is a transverse section through the attachment inlet taken on the line 6—6, Fig. 2;

Fig. 7 is a fragmentary view of the attachment valve operating knob looking in the direction of line 7—7, Fig. 3;

Fig. 8 is a perspective view of one of the parts of the crystal storage chamber; and

Fig. 9 is a perspective view, partly broken away and in section, of one of the members of the attachment which forms a partition between the storage chamber and grinding chamber.

Similar numerals refer to corresponding parts throughout the various figures of the drawings.

A so-called "tank" type suction cleaner is indicated generally at 10 in Fig. 1 having an inlet or suction end 11 and an outlet or exhaust end 12. When the cleaner 10 is operated in the usual manner, a flexible air hose is detachably connected to the inlet end 11 in a suitable manner and a suction nozzle is provided at the free end of the hose for cleaning purposes.

When the cleaner 10 is to be used for blowing pulverized crystals for demotoring treatment and the like, the suction hose is disconnected from the inlet end 11 of the cleaner 10 and may be connected to the cleaner outlet 12 as indicated at 13. The improved unitary crystal grinder attachment of the present invention which is adapted for being held in a hand of the user, generally indicated at 14 is then detachably connected to the outer end of hose 13 and a blower nozzle 15 is mounted on the attachment 14 for discharging crystal-laden air, indicated at 16, onto a surface or into a compartment to be treated.

The attachment 14 may be constructed in any of a number of ways to provide the desired compartments, mechanisms and passages. As shown, it includes a casing or housing member 17 having a cup-shaped portion formed by preferably a cylindrical side wall 18 and a bottom wall 19. A tubular inlet member 20 projects at an angle from (Fig. 2) and is connected substantially tangentially (Fig. 3) with the bottom wall 19 for being telescopically connected to an end of flexible hose 13. The area of the inlet tube is preferably reduced by an internal tubular sleeve 21, the outer end 22 of which communicates interiorly with the tubular inlet 20, and the inner end of which communicates by an opening 23 with the interior of the cup-shaped portion of member 17. The space between the sleeves 20 and 21 may be closed off, as shown, by assembling therewith a crescent-shaped disc 24.

The internal surface of the cylindrical side wall

18 is enlarged to form a shoulder 25 on which a partition member 26 is seated; and another cup-shaped partition member generally indicated at 27, and best shown in Fig. 9, has its enlarged annular flange 28 telescoped within the recessed portion of cylindrical casing wall 18. The annular flange of member 27 is reduced in diameter as indicated at 29 and provided with a shoulder 30 above the enlarged portion 28 thereof, so that the annular flange 31 of crystal hopper member 32 (Fig. 8) may fit telescopically over the reduced flange portion 29 of member 27 and against the shoulder 30 thereof.

The attachment also includes another cup-shaped member generally indicated at 33 for forming the crystal storage chamber. Member 33 has a top wall 34 and an annular cylindrical side wall 35 which is telescoped over the annular flange 31 of member 32 and within the upper end of recessed side wall 18 of casing 17 so that the outer end of wall 35 lies between wall 18 and flange 31, and flange 31 in turn lies between wall 35 and reduced flange 29 of member 27 as shown in Fig. 2. The members 17, 26, 27, 32 and 33 are maintained assembled together by screws 36.

Crystal storage chamber member 33 is provided with an annular tubular neck 37 extending upward from the top wall 34 to form a crystal-receiving opening for the attachment, and neck 37 may be closed by a suitable cap 38 provided with a finger knob 39.

The members 17, 26, 27, 32, 33 and 38 when thus assembled provide three compartments within the attachment, namely, a crystal storage compartment 40 formed by members 32, 33 and 38; a grinding compartment 41 between members 26 and 27; and a driving compartment 42 between members 17 and 26. A central opening 43 is formed in member 27 communicating between the storage compartment 40 and the grinding compartment 41, and another opening 44 in partition member 26 communicates between the driving compartment 42 and grinding compartment 41.

An outlet opening 45 is also formed through the telescoped walls 18 and 28 of members 17 and 27 (Fig. 5) adjacent the opening 44 and communicating between the grinding compartment 41 and the tubular outlet member 46 of the attachment. Tubular portion 47 of discharge nozzle 15 is assembled to the attachment by telescoping the same within outlet member 46.

Partition member 26 is formed centrally with a cup-shaped bearing compartment 48 in which a ball bearing 49 is mounted and retained by disc 50 preferably riveted at 51 to member 26.

A spindle 52 is journalled in bearing 49, preferably constructed as a bolt which clamps disc 53 to the inner race of bearing 49 by nut 54. Disc 53 is formed at its outer edge with blades 55 thus providing an air turbine fan in the driving compartment 42. Nut 54 may be the hub of a disc 56 having a series of blades 57 thereon forming crystal grinding blade means in the grinding compartment 41.

A preferably frusto-conical housing 58 secured to member 27 (Fig. 9) as by spot welding, projects into grinding compartment 41 and surrounds the grinding blade rotor disc 55 and blades 57, as shown. Member 32 is formed with a conical wall 59 providing a downwardly and inwardly sloping bottom for the crystal storage compartment 40, and terminating in a central opening 60 having an ear 61 (Fig. 8) at one side thereof for a purpose to be later described. The

opening 60 is aligned with opening 43 in member 27 and is located immediately above the nut hub 54 of grinder rotor 56.

A valve plate member 62 (Figs. 3 and 4) is pivotally mounted on assembly screw 63 on the top wall 64 of member 27. Valve member 62 has one end 65 projecting through an opening 66 in the side wall of the attachment to which an operating knob 67 is attached. The other end 68 of valve plate 62 normally is located, as shown in Figs. 2 and 3, in a position between openings 43 and 60 closing off communication between said openings. Valve member 62 is normally held in the position shown in Fig. 3 by spring 69.

Further movement of the valve plate 62 in counterclockwise direction (Fig. 3) is prevented by engagement of the end 68 of plate 62 with the ear 61 at the lower end of conical wall 59.

One end 70 of spring 69 may be secured in the telescopied flange walls 35 and 31 of members 33 and 32 (Fig. 2), and the spring then wraps around a sleeve 71 held on screw 63, as indicated at 72, and terminates in an end 73 bent downward at 74 and secured in an opening 75 in valve plate 62. The downturned end 74 of spring 69 is moveable in an arcuate slot 76 formed in wall 64 of member 27.

Thus, the valve 62 is normally spring biased to the position shown in Fig. 3 but may be moved by the operator by pressing knob 67 to the position shown in Fig. 4 whereby communication between the crystal storage compartment 40 and the grinding compartment 41 is established. By controlling the amount of movement of valve plate 62, the amount of crystals fed to the grinding chamber 41 may be regulated so as to control the amount of pulverized material blown out of the attachment.

The crystals (not shown) may be any one of several germicides or disinfectants, as for instance crystalline paradichlorobenzene, which will volatilize at ordinary room temperatures after a short time. The cap 38 for the attachment may be removed in order to introduce crystals into the storage compartment 40 after which the cap is replaced.

When the cleaner 10, hose 13, attachment 14 and nozzle 15 are connected as illustrated in Fig. 1 and crystals are present in compartment 40, the parts may be operated to discharge pulverized crystals entrained in an air blast blown from nozzle 15 onto any desired surface or into any desired compartment. For such purpose, the operator holds the end of hose 13 and the inlet tube 20 of attachment 14 conveniently in one hand, as shown, and points nozzle 15 in the desired direction. The cleaner motor 10 meanwhile is started and the blast of air issuing therefrom through hose 13 passes through reduced tube 22 and opening 23 into driving compartment 42 in a swirling manner. The air then passes through openings 44 and 45 and out through nozzle 15.

The swirling air in driving compartment 42 strikes air turbine blades 55 rotating the disc 53 and spindle 52 therewith at high speed due to the high velocity of the air developed by the constricted size of openings 23, 44 and 45. The speed of rotation of spindle 52 may thus be greater than the speed of rotation of the motor in suction cleaner 10. The rotation of spindle 52 rotates bladed grinder rotor 56 substantially entirely inclosed by housing 58.

When the operator presses knob 67 to the position shown in Fig. 4, valve plate 62 moves to

open position permitting crystals to drop from storage compartment 40 through opening 43 and into the space defined by rotor 56 and housing 58 where the crystals are pulverized or ground by impact by striking and being struck by blades 57 and walls of housing 58. The pulverized crystals drop through the space 77 between the outer peripheral edge of disc 56 and housing 58 and are there entrained by the rapidly rushing air currents passing through the grinding compartment and out through discharge opening 45 and thence out of nozzle 15 as indicated at 16.

Thus the discharge of crystal-laden air is under the direct control of the operator, substantially at the nozzle 15, at all times; and the operator can control the amount of pulverized crystals discharged by regulating the amount that the valve 62 is opened through control of pressure on operating knob 67.

When it is desired to cease the grinding and the discharge of crystals, it is only necessary to release pressure on knob 67 when the spring 69 moves valve 62 to the "off" position of Fig. 3 cutting off the flow of crystals to the grinding chamber. Nevertheless, the air currents continue to pass through the attachment in the manner described and continue to rotate grinder blades 57 without grinding or discharging crystals because the feed of crystals thereto has ceased. In this manner, the operator always knows visibly by the character of the discharged blast when the valve is in "on" or "off" position. Thus it is impossible to stop the device with the valve improperly in "on" position and the grinding compartment cannot become loaded with crystals which might cake therein causing damage to the mechanism.

In its broadest aspects, the invention provides a storage chamber and grinder in a self-contained suction cleaner attachment unit, the grinder blades being driven by a fan which, in turn, is driven by suction cleaner air flow through the attachment which picks up and entrains the ground crystals.

Accordingly, the present invention provides a crystal grinder attachment construction for suction cleaners which eliminates prior art difficulties, solves existing problems in the art and obtains the new results described. Thus the control of grinding and discharging crystals is immediately at the discharge nozzle where it may be instantly regulated by the operator manipulating the nozzle. The grinding mechanism may be operated at a high speed for rapid grinding of the crystals, which speed is not limited by the particular speed at which the suction cleaner motor operates. Complications in the mechanical construction of the suction cleaner per se are eliminated since the grinder is separate from and remote from the cleaner. The grinder attachment is disconnected and removed in entirety when the cleaner is used in the normal manner as a suction cleaner, thus preventing the grinder attachment from reducing the amount of suction available at the nozzle. Furthermore, neither the cleaner nor the attachment can be damaged by caked crystals since loading of the grinding chamber with crystals when the grinder is stopped is eliminated. Finally, the attachment is simple in design and economical to manufacture.

In the foregoing description, certain terms have been used for brevity, clearness and understanding; but no unnecessary limitations are to be implied therefrom beyond the requirements of

the prior art, because such words are utilized for descriptive purposes herein and not for the purpose of limitation and are intended to be broadly construed.

5 Moreover, the embodiment of improved crystal grinder attachment construction illustrated and described is by way of example and the scope of the present invention is not limited to the exact details of construction of the various parts.

10 Having now described the features of the invention, the construction and operation of a preferred embodiment of the improved crystal grinder attachment for a suction cleaner, and the advantageous, new and useful results obtained thereby; the new and useful devices, constructions, arrangements, combinations, sub-combinations, parts and elements and reasonable mechanical equivalents thereof, obvious to those skilled in the art, are set forth in the appended claims.

20 I claim:

1. In a unitary crystal grinder attachment for a suction cleaner which is adapted for being held in a hand of the user, the attachment including 25 a housing having a tubular inlet member adapted for connection with the outer end of a hose and the inner end of the hose being adapted for connection with the exhaust air blast outlet of the suction cleaner, and the housing having a tubular outlet member adapted for connection with a discharge nozzle, walls in the housing forming a storage compartment, a grinding compartment, and a driving compartment, the tubular inlet member communicating with the driving compartment, and there being an outlet 30 opening communicating between the driving and grinding compartments, air turbine means in the driving compartment rotatable by an air blast entering said tubular inlet member, crystal 35 grinder means in the grinding compartment having a driving connection with the air turbine means, valve means interposed between the storage compartment and the grinding compartment for feeding and regulating the flow of crystals from the storage compartment to the grinding compartment, the tubular outlet member of the housing communicating with the grinding compartment; whereby a blast of air entering the driving compartment through the tubular inlet member rotates the turbine to rotate the grinding means to grind crystals fed to the grinding compartment from said storage compartment, and whereby the ground crystals are entrained in the air blast discharged from the tubular outlet member.

40 2. In a unitary crystal grinder attachment for a suction cleaner which is adapted for being held in a hand of the user as set forth in claim 1, and in which the tubular inlet member projects from the housing and includes walls forming an inlet opening of reduced area communicating between said tubular inlet member and said driving compartment.

45 3. In a unitary crystal grinder attachment for a suction cleaner which is adapted for being held in a hand of the user as set forth in claim 1, and in which the compartment forming walls in the housing include a partition wall spaced from said storage compartment and constituting 50 a wall of said grinding compartment, the opening between the driving and grinding compartments being formed in said partition wall, a spindle journaled in said partition wall having fixed at one end thereof an air turbine bladed 55 rotor in the driving compartment and having

fixed at the other end thereof a bladed grinding rotor in the grinding compartment.

4. In a unitary crystal grinder attachment for a suction cleaner which is adapted for being held in a hand of the user as set forth in claim 1, and in which the crystal grinding means includes a rotor in the grinding compartment driven by the air turbine means, and in which there is an opening in one of the walls of the storage compartment communicating with the grinding compartment and the opening being axially of the crystal grinding rotor, and in which the valve means are associated with said opening and varies the size thereof.

5. In a unitary crystal grinder attachment for a suction cleaner which is adapted for being held in a hand of the user as set forth in claim 1, and in which there is an opening in one of the walls of the storage compartment communicating with the grinding compartment and in which the valve means is spring controlled and normally spring biased closed across said opening, and in which

means for actuating said valve means are exterior of the housing.

6. In a unitary crystal grinder attachment for a suction cleaner which is adapted for being held in a hand of the user as set forth in claim 1, and in which the communication between the tubular outlet member and the grinding compartment is adjacent the outlet opening communicating between the driving and grinding compartments.
